UNITED STATES PATENT OFFICE.

DANIEL KOPS, OF NEW YORK, N. Y., ASSIGNOR TO KOPS BROTHERS, INC., OF NEW YORK,
N. Y., A CORPORATION OF NEW YORK.

APPAREL CORSET.

Application filed April 20, 1923. Serial No. 633,363.

To all whom it may concern:

Be it known that I, DANIEL Kops, a citizen of the United States, residing in the borough of Manhattan, city, county, and 5 State of New York, have invented an Improvement in Apparel Corsets, of which the following is a specification.

This invention relates to an apparel corset and more particularly to that type of corset 10 garment in which self-reducing straps are employed. Heretofore, as I am aware, apparel corsets embodying self-reducing straps have also been constructed to include tension straps placed in the lower front portions of 15 the garment to lie immediately above the groin section of the wearer to assist in molding and supporting the lower abdominal region of the wearer. In this type of garment, however, it has been customary to employ skirt extensions and to provide the 20 usual hose supporters which maintain the skirt portions and the lower front portions of the garment in position when the wearer is standing, but the tension exerted by the 25 hose supporters being more or less released when the wearer is seated there is no provision in this type of garment for maintaining the lower front portions thereof, including the skirt sections, in place when the wearer is seated. So far as I am aware no provision 30 has been made heretofore to mold or confine the upper portion of the thigh and to maintain the skirt section of the garment in position when the wearer is seated. The object 35 of my present invention is primarily to overcome this difficulty and in carrying out the same I provide an apparel corset in which in the lower front portions thereof there are self-reducing straps preferably adjustable to position and underlying tension 40 straps which are so placed as to overlie the upper portion of the thigh immediately below the groin section to maintain the lower front portions of the garment, including the skirt section, in position when the wearer is standing to confine and mold this portion of the body, and when the wearer is seated to fit the thigh immediately below the groin 45 section to maintain the skirt section of the garment in place. The corset made in accordance with my invention will be herein-after more particularly described in con-

junction with the accompanying drawing in which,—

Fig. 1 is a perspective view illustrating 55 my improved corset garment.

Fig. 2 is a similar view on a smaller scale showing the positions of the garment when the wearer is seated.

Fig. 3 is an enlarged partial front elevation, and

Fig. 4 is a similar view showing the inside of the corresponding part of the garment shown in Fig. 3.

The corset made in accordance with this 65 invention is preferably constructed in the usual corset body halves illustrated at 10 and 11 and adapted to be connected at the back with the usual laces. At the front the corset body halves are provided with front steels 70 12 and 13 secured in the usual manner in the front steel sections 14 and 15. One of the front steels is provided with a series of spaced sockets 16 adapted to receive a correspondingly spaced series of studs 17 on the 75 other corset steel to connect the parts of the garment at the front thereof. Below the front steels the front steel sections are provided with extensions 18 and 19 depending appreciably below the lower ends of the 80 steels. One of these front extensions is fitted with a hook 20 and the other with an eye 21 adapted to be engaged to connect the extensions to one another. The right corset body half is provided with a skirt 22 and the left 85 corset body half with a skirt 23. These skirts are provided with front extensions 24 and 25 respectively in a manner similar to that employed in corset garments in which self-reducing straps are employed. 90

The self-reducing straps, the tension straps and the manner in which they are secured in the garment are similar in both corset body halves, the parts, as will be understood, being placed in oppositely disposed positions 95 and for which reason the self-reducing strap, the corresponding tension strap and the parts associated therewith will be described in one corset body half only. The self-reducing strap is indicated at 26 and as is 100 customary this is secured in the body of the garment distant from the front steel section along a line of stitching indicated at 27, the strap being connected in the garment from

the points indicated at 28 and 29. The strap 26 extends forwardly from its line of connection in the garment and at its free forward edge is fitted with a series of spaced 5 eyelets 30, either one of which is adapted to engage with a stud 31 fixed in the lower portion of the corresponding front steel in order to adjust the self-reducing strap to position. The self-reducing strap includes a 10 downward extension 32 which at its lower extremity is secured to the edge of the skirt extension 24 along the line of stitching indicated at 33, and as is also customary the skirt extension 24 is cut away as indicated 15 at 34 leaving an appreciable gap between the forward edge of the skirt extension and the adjacent edge of the extension of the front steel section.

The invention also includes a tension 20 strap 35 made of elastic or other similar yielding material and preferably secured at one edge in the line of stitching 27 in which the self-reducing strap is connected to the body of the garment and by which the extension 24 of the skirt section is also connected to the skirt. This strap 24 lies between the self-reducing strap and the extension thereof and the adjacent portions of the skirt extension and the extension of 25 the front steel section, and at its opposite end is connected to the extension of the front steel section along the line of stitching indicated at 36 so as to assume a substantially circumferential position in the 30 garment.

The front portion of each corset body half of the garment is preferably fitted with stay members illustrated as being employed in pairs and designated at 37, 38 and 40 39 respectively, the lower ends of these stay members extending appreciably below the upper edge of the self-reducing strap and being spaced appreciably from the upper edge of the corresponding tension strap. 45 Also as is customary, the extension of the front steel sections is provided with a hose supporter indicated at 40 and the extremity of the tension strap extension and the lower forward end of the skirt extension to which 50 it is connected are fitted with a hose supporter 41, these parts being connected preferably along the same lines of stitching, that is to say the hose supporter 41 is secured in the garment by the same lines of stitching as indicated at 33 which connect the lower extremity of the self-reducing strap to the lower forward edge of the skirt extension.

The self-reducing straps are placed in the 60 garment in the usual manner and perform the function of shaping, molding and reducing the abdominal section of the body of the wearer. The tension straps are so placed in the garment as to extend across the upper front portions of the thigh to

maintain the skirt sections in position when the wearer is standing and to confine and mold this portion of the body to the desired shape, whereas when the wearer is seated the tension straps assume a position in 70 which the upper edges thereof lie in the groin section of the wearer and obviously they exert a tension on the skirt section of the garment to maintain the same in place when the wearer is seated.

I claim as my invention:

1. In an apparel corset and in each corset body half thereof, a front steel section having an extension, a skirt depending below the groin line of the wearer, a self-reducing strap secured to the garment distant from the front steel, means for adjusting the self-reducing strap to position at the lower end of the front steel, and a tension strap extending from the depending portion of the front steel section rearwardly being substantially coextensive with the self-reducing strap and connected to a portion of the skirt below the groin of the wearer so that the said tension strap extends across the upper front portion of the thigh and lies immediately below the groin of the wearer to exert a tension and maintain the skirt section in position across the thigh when the wearer is seated.

2. In an apparel corset and in each corset body half thereof, a front steel section having a portion depending below the groin of the wearer, a skirt section also extending below the groin of the wearer, a self-reducing strap secured along one edge in the body of the garment extending forwardly and adjustably connected to the front steel, the self-reducing strap having a downward extension and the skirt a forward extension, a hose supporter connected to the extension of the self-reducing strap and the extension of the skirt member to exert a downward tension in the self-reducing strap and a lateral tension in the skirt member when the wearer is standing, and a tension strap connected at one end to the depending extension of the front steel section and at the other end to the skirt member so as to extend across the upper front portion of the thigh and to lie immediately beneath the groin of the wearer to maintain the skirt section in position across the thigh when the wearer is seated.

3. In an apparel corset and in each corset body half thereof, a front steel section having a portion depending below the groin line of the wearer, a skirt section also extending below the groin line of the wearer, a self-reducing strap secured along one edge in the body of the garment extending forwardly to the front steel section at which the forward edge of the self-reducing strap is adjustably connected to the front steel, the self-reducing strap having a downward

extension and the skirt member a forward extension, a hose supporter connected to the extension of the self-reducing strap and also to the forward end of the extension of the skirt member to exert a downward tension in the self-reducing strap and a lateral tension in the skirt member to maintain the skirt member in position when the wearer is standing, the said extension of the skirt member also being provided with a cut away portion, and a tension strap lying in a position circumferentially of the garment and extending from the depending portion of the front steel section to a portion of the

skirt member which is below the groin line 15 of the wearer, the said tension strap lying between the extension of the skirt member and the extension of the self-reducing strap and overlying the upper front portion of the thigh when the wearer is seated to assume a position immediately below the groin 20 of the wearer to maintain the skirt member in position over the thigh when the wearer is seated.

Signed by me this 24th day of March, 1923.

DANIEL KOPS.
